R. M. ANDERSON.
MOVING PICTURE FILM REEL.
APPLICATION FILED MAR. 23, 1917.

1,266,379.

Patented May 14, 1918.

By his Attorney Rudolph M. Anderson

UNITED STATES PATENT OFFICE.

RUDOLPH M. ANDERSON, OF NEW YORK, N. Y.

MOVING-PICTURE-FILM REEL.

1,266,379.

Specification of Letters Patent. Patented May 14, 1918.

Application filed March 23, 1917. Serial No. 157,049.

To all whom it may concern:

Be it known that I, RUDOLPH M. ANDERSON, a citizen of the United States, residing in the city of New York, in the county of Bronx and State of New York, have invented certain new and useful Improvements in Moving-Picture-Film Reels, of which the following is a specification.

This invention relates to improvements in reels, and particularly to those adapted to contain films such as are used in moving picture machines.

The principal object of the invention is to provide a reel of improved construction, in which the securing means, whereby the side elements are held together, are so disposed as to present a relatively smooth surface without outstanding projections.

A further object is to provide fastenings whereby the side elements of the reel are constrained together and with relation to the central hub or core, the fastenings being operable from either side of the reel, and finally, to provide a reel of pleasing appearance, simple in construction, and inexpensive to manufacture.

These and other like objects are attained by the novel construction and combination of parts hereafter described and shown in the accompanying drawing, forming a material part of this disclosure, and in which:—

Figure 1 is a side elevational view of a reel made in accordance with the invention.

Fig. 2 is an enlarged transverse sectional view taken on line 2—2 of Fig. 1.

Fig. 3 is a similar transverse sectional view taken substantially in the same plane, but illustrating a modification in construction.

Fig. 4 is a fragmental plan view of the parts shown in Fig. 2.

Fig. 5 is a similar fragmental plan view of the parts shown in Fig. 3, and Fig. 6 is a similar view of a further modification.

The reel is comprised of two sheet metal circular disks 10, preferably formed with a beaded peripheral edge 11, and having a plurality of openings 12 for the purpose of lightening the structure and through which the edges of the reeled material can be seen.

Radially formed ribs 14 extend from the rim 11 to a raised ring 15, in which may be formed a concentric depression 16, adapted to engage with a central core or hub 18, so that the two side disks are held in register.

In the form shown in Figs. 1, 2 and 4, a

number of areuate depressions 20 are formed in the surface 16, the depressions having a perforation 21 from which extends a slot 22, permitting the shanks of the bolts or securing elements 25 to enter, while the perforations 21 are adapted to receive the heads 26 formed at both ends of the bolts 25, the same passing through equally spaced longitudinal openings formed in the core 18.

At the center of the disk is a through opening 28, having a keyway 29, the opening and keyway being suited to the keyed shaft upon which the reels are rotated.

The operation of assembling is as follows:—

The core 18, being placed in the recess 16, formed in the disks 15, the bolts are entered, the heads 26 resting in the areuate cavities 20 on one side, the opposite ends passing through the openings 21, it being understood that the disks are pressed firmly together, whereupon one of the disks is turned with relation to the other, the twisting movement causing the heads 26, protruding through the opening 21, to pass to the other end of the recesses 20, holding the disks firmly together.

In the forms shown in Figs. 3 and 4, a somewhat similar form of construction is employed, the side plates or disks 10 being formed at the center with a recess 16, whereby the core 18 is held in adjusted position, the core being provided with a plurality of equally spaced longitudinal passages 35 in which are inserted tubes 36, internally screw-threaded at their ends and receptive of the screws 38, the beveled heads 39 of which are flush when within the depressed or countersunk portions 40 of the disks 16, it being understood that the length of the tubes 36 is such as to permit the countersunk portions 40 to be drawn tightly into the ends of the wooden core, the tube acting in the manner of a nut for the screws 38, the heads of which are as indicated, level or flush with the surrounding surface.

In the modification shown in Fig. 6, a through bolt 42 is engaged in the core 18, the head 43 being seated in a countersunk depression in the plate 16, a similar depression being formed in the opposite plate receptive of the nut 44, the construction being such as to hold the parts rigidly together.

In order to increase the longevity of the reel, particularly with respect to the core and provide means whereby it will not rotate

or become loose on the shaft and its driving key, a plurality of keyways or slots 19 are made in the core 18, the same being located with reference to the holding means by 5 which the plates are engaged, so that when one keyway becomes worn it is easily possible, by releasing the holding means, to turn the core with relation to the plates and again tighten in a new position, thus substituting 10 an unworn keyway in the core and assuring its registration with the keyways 29 in the plate.

Having thus described my invention, what I claim as new, and desire to secure by Letters Patent, is:—

1. In a reel, the combination with a pair of circular disks, a central annular raised seat formed in said disks, having a plurality of perforate arcuate depressions therein, of 20 a solid core receivable in said seats, said core having a plurality of longitudinal passages therethrough, bolts having rigid heads formed at each end engageable with the perforate arcuate depressions in said disk seats, 25 said rods passing through the passages in said core, and means combined with said arcuate depressions for maintaining said bolts against displacement.

2. In a reel, the combination with a pair 30 of symmetrically formed circular plates, and a core adapted to be secured therebetween, of recessed seats formed in said plates receptive of the ends of said core, a plurality of tubes inserted at spaced intervals concentrically in said core, countersunk depres-

sions formed in said recessed seats, and screws having beveled heads receivable in said countersunk depressions, said screws being engageable with threads in the ends of said tubes.

3. A reel comprising a pair of circular disks, a spacing core therebetween, a plurality of metallic tubes, screw-threaded internally at their ends, inserted in said core, 40 said tubes being of lesser length than the core, and countersunk screws insertible through said disks engageable with said tubes, the heads of said screws being substantially level with the surface of said disks and operable from either side of the reel.

4. A reel comprising a pair of disks having a central raised seat containing an opening and a single keyway formed therein, of a relatively soft core centered between said disks, said core having a central opening and a plurality of equally spaced keyways formed 55 therein, fastenings enterable through said disks, said fastenings corresponding in number and spacing with the keyways in said core, and means of securing said fastenings.

5. A reel comprising a pair of disks, a soft core centered between said disks, a plurality of uniformly spaced keyways in said core, a corresponding number of bolts passing through said disks and screw-threaded into said cores, and means for engaging said bolts beyond one of said disks.

In testimony whereof I have signed my name to this specification.

RUDOLPH M. ANDERSON.
